[57] CLAIM

The ornamental design for a interdental brush handle, as shown and described.

DESCRIPTION

FIG. 1 is a right side elevational view of an interdental brush handle showing my new design;

FIG. 2 is a front elevational view thereof;

FIG. 3 is a rear elevational view thereof;

FIG. 4 is an end elevational view thereof;

FIG. 5 is a left side elevational view thereof;

FIG. 6 is an opposite end elevational view thereof;

FIG. 7 is a fragmentary right side elevational view of one end of the handle, the holder shown in a closed position;

FIG. 8 is a fragmentary front elevational view of one end of the handle, the holder shown in a closed position;

FIG. 9 is a fragmentary rear elevational view of one end of the handle, the handle shown in a closed position;

FIG. 10 is a fragmentary end elevational view of one end of the handle, the holder shown in a closed position;

FIG. 11 is a fragmentary left side elevational view of one end of the handle, the holder shown in a closed position;

FIG. 12 is a fragmentary cross-sectional opposite end elevational view of one end of the handle, the holder shown in a closed position; and,

FIG. 13 is a fragmentary right side elevational view of one end of the handle, the holder shown in a closed position.
